UNITED STATES PATENT OFFICE.

JULIUS LAWITZKA, OF PEORIA, ILLINOIS.

CAR-BRAKE.

SPECIFICATION forming part of Letters Patent No. 408,916, dated August 13, 1889.

Application filed April 20, 1889. Serial No. 307,994. (No model.)

To all whom it may concern:

Be it known that I, JULIUS LAWITZKA, of Peoria, in the county of Peoria and State of Illinois, have invented certain Improvements 5 in Car-Brakes, of which the following is a specification.

My invention relates to an automatic brake or stop to prevent retrograde motion of cars ascending inclined tracks—such, for example, 10 as the tram-cars of miners.

The invention is directed particularly to the production of a brake which may be applied to cars of ordinary construction without requiring change or alteration thereof, and 15 which shall act upon both the wheels and the rails.

In the accompanying drawings, Figure 1 is a side elevation of the rear end of a car having my improvements applied thereto. Fig. 2 is a rear elevation of the same. Fig. 3 is a section on the line $\alpha\alpha$ of Figs. 1 and 2, looking downward. Fig. 4 is a section on the line yy , looking downward. Fig. 5 is a section on the line zz .

25 Referring to the drawings, A represents a car-body, and B one of its supporting-wheels. These parts may be constructed in any ordinary manner.

C represents an upright arm loosely suspended 30 from the car-body in position to act against the rear face of the wheel and having at its lower end devices to grip the rail in the event of the car moving backward. The arm may be suspended by any suitable devices. 35 As shown in the drawings, its upper end is passed through a vertical slot in a bracket-plate D, bolted rigidly to the car. This bracket-plate is opened at the rear end to permit the insertion of the arm. The arm is 40 sustained by a pin d, and is prevented from escaping by a pin d', inserted through the rear end of the bracket across the slot. This pin d' is provided, as shown in Fig. 6, with a locking-lip d and with a downwardly-turned 45 end d''. The pin is inserted through a key-hole opening, and the weight serves to hold it in a locked position.

The forward face of the arm C is adapted 50 to fit the periphery of the wheel and act frictionally thereon after the manner of an ordinary brake-shoe. At its lower end the arm

C is provided with two pivoted gravitating dogs e e', the lower ends of which lie in opposite sides of the rail E. These dogs are supported, as shown in Fig 5, by square pivots 55 e², passing through and fixed rigidly to a stirrup e⁴, provided at the rear end with a weight e⁵, the construction being such that the dogs may swing rearward and upward clear of the rail, as indicated by the dotted lines in Fig. 1. 60

The lower end of the arm C has at the lower end a rearwardly-extended portion F, provided with two vertical slots f and f', which converge toward the front, and through which the lower ends of the respective dogs 65 extend, as shown. The weighted stirrup, by turning the pivot, urges the lower ends of the dogs downward and forward, so that the forward ends of the converging slots draw them laterally into contact with the rail on 70 opposite sides. As the car moves forward the dogs swing to the rear and ride smoothly and easily along the rail. In the event, however, of a retrograde motion of the car, the dogs are turned by the converging slots into 75 forcible contact with the rail. In this manner the lower end of the arm C is locked rigidly to the truck, so that it serves to arrest the backward motion of the car, first, by its action as an abutment behind the wheel, and, second, 80 by its frictional effect on the periphery of the wheels.

When the car is to move backward, the dogs are thrown out of engagement by turning the stirrup e⁴ upward, the effect of which 85 is to carry the dogs rearward and upward clear of the rail. This elevation of the stirrup may be effected by means of a chain f², attached thereto and leading upward to the car or by any equivalent operating device. 90

Having thus described my invention, what I claim is—

1. In combination with a railway-car, an arm C, jointed to the car-body, arranged to act against the rear face of the wheel, and 95 provided at the lower end with gravitating dogs to engage the rail.

2. In combination with a railway-car, the stop device consisting of the standard, its lower arm provided with converging slots, 100 and the two gravitating dogs passing through said slots on opposite sides of the rail.

3. In combination with a car, the pendent arm C loosely jointed thereto, arranged to act against the face of the wheel, and provided with converging slots at the lower end, 5 in combination with a weighted stirrup and two gravitating dogs independently pivoted to the stirrup and adapted to engage opposite sides of the rail.

In testimony whereof I hereunto set my hand, this 16th day of March, 1889, in the presence of two attesting witnesses.

JULIUS LAWITZKA.
